UNITED STATES PATENT OFFICE.

RUSSELL E. SARD, OF ALBANY, NEW YORK.

DESIGN FOR A GAS-RANGE.

45,157.

Specification for Design.

Patented Jan. 13, 1914.

Application filed October 21, 1913. Serial No. 796,535. Term of patent 3½ years.

To all whom it may concern:

Be it known that I, RUSSELL E. SARD, a citizen of the United States, residing in the city of Albany, county of Albany, and State of New York, have invented a new, original, and ornamental Design for Gas-Ranges, of which the following is a specification, reference being had to the accompanying drawing, forming part thereof.

Figure 1 is a front elevation and Fig. 2

is a side elevation of gas range showing my new design.

I claim:

The ornamental design for a gas range as shown.

RUSSELL E. SARD.

Witnesses:

FREDERICK W. CAMERON,
BEULAH CARLE.
